UNITED STATES PATENT OFFICE

EMIL FREY, OF BIENNE, SWITZERLAND, ASSIGNOR, BY MESNE ASSIGNMENTS, TO
PERPETUAL SELF WINDING WATCH CORPORATION, OF NEW YORK, N. Y., A COR-
PORATION OF DELAWARE

SELF-WINDING WATCH

Application filed November 1, 1930, Serial No. 492,630, and in Switzerland December 5, 1929.

This invention relates to watches and more particularly to wrist watches provided with self-winding mechanism. In such watches, a pivoted pendulum is provided and is caused to swing by motions of the wearer's arm, means being provided to utilize the pendulum swing to actuate the winding train.

5

In the elongated type of self-winding wrist watch disclosed in the co-pending application of Max Reiner, Ser. No. 489,541, filed Oct. 18, 1930, the pendulum is pivoted to the movement adjacent one end thereof and is provided with a weighted head offset so that its path of swing overlies one end of the 10 movement.

An object of this invention is to anchor a watch movement of this type securely in an elongated case in such manner as to provide maximum free space for the weighted portion 15 of the pendulum to swing in.

According to this invention, the side walls of the case are provided with shoulders which engage the movement frame to hold in contact with one end of the case that end of the 20 movement frame to which the pendulum is pivoted. The movement is thus securely anchored in the case and the end of the case allotted to the weight portion of the pendulum is entirely unobstructed.

Other objects, novel features and advantages of this invention will be apparent from the following specification and accompanying drawing, wherein:

Fig. 1 is a front view of an assembled 30 watch with the cover open;

Fig. 2 is a similar view of the case with the movement removed;

Fig. 3 is a section on the line 3—3 of Fig. 2; and

Fig. 4 is an elevation of the movement.

The case consists of an elongated main or body portion to which is pivotally connected the cover 11 having a central aperture in which is provided a crystal 12. The cover is also provided with rods 13 and 14 to which are attached the ends of the strap by means of which the watch is secured to the wearer's arm. A flange 15 extends inwardly from the upper end of the body portion 10, this flange being provided along the major portion of

two sides of the case and across one end. At each end the flange is provided with inwardly extending lugs 16.

The movement is supported by a frame 17 of proper configuration to be received in the 55 recess defined by the inner edges of the flange 15. The lugs 16 engage shoulders 17a provided on the frame and anchor it securely in position. A pendulum 18 is pivoted to the frame 17 at 19 and is provided with a weighted head which swings in the space provided between the end of the frame and the end of the watch case. This space is entirely unobstructed thereby permitting the use of a 60 large weight.

An oblong dial 20 is supported by the frame and is provided with the usual hour numbers. The aperture in which the glass 12 is supported is of sufficient size that the numbers are all clearly visible when the cover is 70 closed on the main portion of the watch.

It is of course apparent that various modifications may be made in the structure above described without in any way departing from the spirit of the invention as defined in the 75 appended claims.

I claim:

1. In combination, an elongated case, a self-winding watch movement comprising a frame of less length than the case and a 80 winding pendulum pivoted to such frame adjacent one end thereof and extending substantially lengthwise thereof, said pendulum having a weighted portion offset from the remainder overlying the other end of the movement and lugs projecting inwardly from said case into engagement with said frame to anchor it with the first named end thereof in contact with one end of said case.

2. In combination, an elongated self-wind- 90 ing watch movement having a winding pen-
dulum pivoted thereto adjacent one end and extending substantially lengthwise thereof, said pendulum having a weighted portion 95 offset from the remainder and overlying the other end of said movement, and an elongated case in which said movement is contained, said case being provided with shoulders en-
gaging said movement to anchor it in said 100 case with the end of the movement to which

the pendulum is pivoted in contact with the corresponding end of the case.

3. In combination, an elongated self-winding watch movement having a winding pendulum pivoted thereto adjacent one end and extending substantially lengthwise thereof, said pendulum having a weighted portion offset from the remainder and overlying the other end of said movement, and an elongated case in which said movement is received, said case being provided with shoulders to engage said movement to anchor it with the first named end thereof in contact with the corresponding end of the case.

15 In testimony whereof, I have signed my name to this specification.

EMIL FREY.
